UNITED STATES PATENT OFFICE

165,692

MILK PROCESSING BUILDING

Peter B. Mayo, Northfield, Ill.

Application October 26, 1950, Serial No. 12,741

Term of patent 7 years

(Cl. D13—1)

To all whom it may concern:

Be it known that I, Peter B. Mayo, a citizen of the United States residing at Northfield, in the county of Cook, State of Illinois, have invented a new, original, and ornamental Design for a Milk Processing Building, of which the following is a specification, reference being had to the accompanying drawings forming a part thereof, wherein:

Figure 1 is a front elevational view of a milk processing building, showing my new design;

Figure 2 is a side elevational view of the right hand side thereof as shown in Fig. 1; and

Figure 3 is a side elevational view of the left hand side thereof as shown in Fig. 1.

The dominant features of my design reside in the portions shown in solid lines.

I claim:

The ornamental design for a milk processing building, substantially as shown and described.

PETER B. MAYO.
